COAGULATOR

Charles R. Storz, Jr., Jefferson County, Mo., assignor to Storz Instrument Company, St. Louis, Mo., a corporation of Missouri

Application February 7, 1951, Serial No. 14,121

Term of patent 7 years

(Cl. D83—1)

To all whom it may concern:

Be it known that I, Charles R. Storz, Jr., a citizen of the United States, residing in Jefferson County, Missouri, have invented a new, original, and ornamental Design for Coagulator, of which the following is a specification, reference being had to the accompanying drawings, forming part hereof.

Figure 1 is a top view of a coagulator, embodying the new design.

Figure 2 is a side view of the coagulator.

Figure 3 is an end view looking towards the left hand end of the coagulator, as shown in Figure 2.

Figure 4 is an end view looking towards the right hand end of the coagulator, as shown in Figure 2.

I claim:

The ornamental design for a coagulator, as shown.

CHARLES R. STORZ, JR.
